UNITED STATES PATENT OFFICE.

EDWARD D. HANCOCK, OF JOHNSTOWN, PENNSYLVANIA.

REINFORCING MEMBER.

1,280,454.

Specification of Letters Patent.

Patented Oct. 1, 1918.

Application filed May 17, 1917. Serial No. 169,219.

To all whom it may concern:

Be it known that I, EDWARD D. HANCOCK, a citizen of the United States, and a resident of the city of Johnstown, county of Cambria, and State of Pennsylvania, (whose post-office address is Johnstown, Pennsylvania,) have invented certain new and useful Improvements in Reinforcing Members; and I do hereby declare the following to be 10 a full, clear, and exact description of the invention, such as will enable others skilled in the art to which it appertains to make and use the same.

My invention relates to metal shear bars 15 in the form of hooks adapted to be used to anchor reinforcing bars more firmly into the concrete and to strengthen the construction as a whole, thereby increasing the efficiency of the reinforcing bars.

20 My invention relates particularly to a construction comprising a plurality of shear bars, each made of a metal hook formed of bars provided with alternating projections and depressions adapted to fit into or interlock with corresponding alternating projections and depressions of the reinforcing bar. By reason of this construction, the 25 internal stresses in a reinforced girder become so rearranged that the girder is 30 stronger for its size.

The primary feature of the design of this hook lies in its adaptability to be applied at any time before the concrete is poured and it can be applied at any location desired without disturbing any of the bars already in place since it requires no extra appliances, except perhaps a piece of wire for convenience in erection, thus giving a 35 firm and strong connection to the main bar 40 without the use of clamps, ties or other special appliances.

My construction is particularly adapted to bars having a central body portion, and a plurality of projections beyond the body 45 portion, which projections may be curved or corrugated, the opposite edges of each pair of corrugations being parallel to each other, whereby the projections on each bar will neatly fit the depressions of a shear bar of 50 the same kind. I wish it understood, however, that my construction is also adapted to other forms of reinforcing bars and particularly to those which have alternating projections and depressions on their surfaces 55 adapted to contact or interlock with corre-

sponding depressions or projections on the shear bar of similar outline.

Having thus given this general description of my invention, I will now, in order to make the same more clear, refer to the one 60 sheet of drawings accompanying and forming part of this specification, and in which like figures refer to like parts.

Figure 1 is a side elevation of a part of a reinforcing member embodying my invention; Fig. 2 is a top plan view of that portion of the bar illustrated in Fig. 1; Fig. 3 is a vertical transverse sectional elevation taken on the line III—III of Fig. 2; Fig. 4 is a vertical transverse sectional elevation 70 taken on the line IV—IV of Fig. 2; and Fig. 5 is a side elevation of the entire reinforcing member on a reduced scale.

Referring now to the characters of reference on the drawings:—1 indicates a reinforcing bar with alternating projections or curved portions 2, and depressions 3. 4 indicates the shear bar which is bent into the form shown in the drawings, provided with a hook end 12, and a diagonally projecting 80 portion 5 integral therewith. This shear bar 4 is made from a bar similar to the main reinforcing bar having similar projections 6 and depressions 7, so that the projections of the shear bar will fit into the 85 depressions of the main reinforcing bar, thus firmly locking the bars together so that no longitudinal movement is possible. 8 indicates the flattened portion of the shear bar 4 near the diagonally projecting end 5, on 90 the bent portion 9, while 10 indicates the flattened portion of the shear bar 4 near the hooked end 12 on the bent portion 11. This flattening of the corrugations or projections 6 on the bent portions 9 and 11 of the shear 95 bar 4 will prevent interference with the projections on the bar 1 and permit the bars to be fitted closer together. 13 indicates stay wires which are for the purpose of holding 100 the bars together temporarily until the concrete is poured.

Although I have described and illustrated my invention in considerable detail, I do not wish to be limited to the exact and specific details thereof as shown and described, but 105 may use such modifications in, substitutions for, or equivalents thereof, as are embraced within the scope of my invention, or as pointed out in the claims.

Having thus described my invention, what 110

I claim and desire to secure by Letters Patent is:—

1. A reinforcing structure comprising a bar provided with a plurality of projections, 5 a shear member provided with a similar plurality of projections, adapted to contact and interlock with the projections of the bar aforesaid, one end of said shear member being offset and bent to partially surround 10 said bar, the other end being offset and bent at an angle to said bar.

2. A reinforcing structure comprising a bar provided with a plurality of sinuous projections and depressions, a shear member 15 provided with a similar plurality of sinuous projections and depressions, a portion of said shear member being adjacent to the bar aforesaid with its projections, within the depressions of the bar, thereby being longitudinally fixed relative thereto, the shear member being offset and having a hooked end adapted to partially surround said bar, the other end of said shear member being offset and projecting at an angle to the bar 20 aforesaid.

3. A reinforcing member comprising a bar provided with a plurality of projections and depressions, a shear bar comprising a main body portion, one end of which is 25 offset and bent to form a diagonally projecting portion, the other end being offset and bent into a hook-shape adapted to partly surround the reinforcing bar, said shear bar having a plurality of projections and de-

pressions adapted to fit into the depressions 35 and projections of said reinforcing bar, thus firmly locking the bars together.

4. A reinforcing member comprising a bar provided with a plurality of sinuous projections and depressions, a shear bar of substantially similar conformation, having one end offset and bent to form a diagonally projecting portion, the other end being offset and bent into hook-shape adapted to partly surround the reinforcing bar, said attached 45 shear bar being provided with sinuous projections and depressions adapted to fit into and interlock with the corresponding depressions and projections of the reinforcing bar, whereby no relative longitudinal movement is possible.

5. A reinforcing member comprising a bar, having a plurality of corrugated flanges on at least one of two opposite sides, a shear bar of similar cross-section, one end of which 55 is offset and bent to form a diagonally projecting portion, the other end being offset and bent into hook-shape adapted to partly surround the reinforcing bar, said attached shear bar having corrugated flanges adapted 60 to fit the corrugations of said reinforcing bar and interlock with it, thereby preventing longitudinal movement, and means for holding the bars together while the concrete is poured.

In witness whereof I hereunto affix my signature.

EDWARD D. HANCOCK.
